CLAIM

The ornamental design for a marine vessel drop-in module, as shown and described.

DESCRIPTION

FIG. 1 is a front perspective view of the marine vessel drop-in module;

FIG. 2 is a left side elevational view thereof, wherein the right side elevational view is a mirror image thereof;

FIG. 3 is a top plan view thereof;

FIG. 4 is a bottom plan view thereof;

FIG. 5 is a rear elevational view thereof; and,

FIG. 6 is a front elevational view thereof.
